UNITED STATES PATENT OFFICE.

STANLEY R. HUGHES, OF BENTON, AND HARRY D. HUGHES, OF LYTHE, TEXAS.

OIL-PUMP.

1,379,690.

Specification of Letters Patent. Patented May 31, 1921.

Application filed October 18, 1917. Serial No. 197,278.

To all whom it may concern:

Be it known that we, STANLEY R. HUGHES and HARRY D. HUGHES, citizens of the United States, residing at Benton, and Lytle, 5 in the county of Atascosa, State of Texas, have invented certain new and useful Improvements in Oil-Pumps; and we do hereby declare the following to be a full, clear, and exact description of the invention, such as 10 will enable others skilled in the art to which it appertains to make and use the same.

This invention is an improvement in pumps and has particular reference to a pump for dispensing oils and other liquids.

15 An object of the invention is to provide a pump which may be detachably secured to a barrel or other container and operated to dispense the liquid therefrom in predetermined quantities and thereby avoid the 20 necessity of emptying the contents of the barrel into a tank, as usual.

Another object is to provide a pump of this character which is comparatively simple in construction, easy to manufacture and 25 effective in carrying out the purposes for which it is designed.

The inventive idea involved is capable of receiving a variety of mechanical expressions one of which, for the purpose of illustrating the invention, is shown in the accompanying drawings, wherein:—

Figure 1 is a side elevation of the pump showing the same attached to a barrel.

Fig. 2 is a fragmentary vertical longitudinal section.

Fig. 3 is a top plan view.

Fig. 4 is a similar view with the top portion of the frame removed and showing the gearing for operating the rack member and 40 registers.

It is customary, in dispensing oils and other liquids shipped in barrels, to pour the liquids from the barrels into suitable containers such as tanks before dispensing the 45 same. This procedure has been found inconvenient and expensive and owing to the loss of the liquids and time involved in emptying the same.

The present invention, a preferred form 50 of which is illustrated in the accompanying drawings, is designed to overcome the above objection and, to this end, use is preferably made of a pump cylinder 10 having a detachable hopper bottom 11 which terminates 55 in a restricted tube 12 adapted to be extended through the top of a barrel 13 to

a point adjacent the bottom thereof. The lower end of the tube 12 is provided with a valve seat 14 including a spider 15 in which the stem 16 of the vertical movable 60 valve 17 is mounted, said valve being adapted to open and close to permit the liquid in the barrel to be drawn into the tube 12 and retained therein.

Means are provided for supporting the 65 pump upon the top of the barrel and comprises a plurality of supporting arms 18 disposed radially with respect to the tube 12 and having their inner ends pivotally connected, by pins 19, to the collar 20 secured 70 to the tube 12 adjacent the bottom 11 by means of the set screw 21. The outer end of each of the arms 18 is provided with the clamping jaws 22 connected by the adjusting bolt 23 employed to adjust one of 75 the jaws relative to the other whereby to securely clamp the same into engagement with the rim of the barrel.

The upper end of the cylinder 10 is preferably provided with a removable top 24 80 having a central opening 25 therein through which the piston plunger or rod 26 extends and mounted upon the top 24 is a stuffing box 27 in which the plunger 26 is movable. The top 24 further carries a faucet 28 85 through which the liquid in the cylinder is dispensed in a manner to appear in the course of the description.

The lower end of the plunger 26 is detachably mounted in the spider 29 of the 90 valved piston of plunger 30 having a central valve seat engaged by the vertical movable valve 32. It will be apparent from the foregoing description taken in connection with the drawings that when the piston 30 95 is moved upwardly in the cylinder 10 the liquid above said piston will retain said valve 32 in closed position and said liquid will be forced upwardly through the faucet 28. During said upward movement of the 100 piston the suction created thereby will open the valve 17 at the lower end of the tube 12 and thus draw the liquid in the barrel upwardly through said tube and into the cylinder 10 beneath the piston 30. When the 105 said piston starts its downward movement the pressure beneath the same will open the valve 32, permitting the liquid to pass into the upper part of the cylinder above said piston and at the same time said pressure 110 will close the valve 17 and thus prevent any more of the liquid from the barrel entering

said tube until the piston again starts its upward movement. In this manner a pre-determined amount of liquid (the capacity of the cylinder) may be dispensed through 5 the faucet 28.

- The mechanism for reciprocating the rod 26 and consequently the valve 30 preferably comprises the vertically disposed rack bar 39 slidably mounted upon the side of the 10 cylinder 10 and connected at its upper end to the rod 26 by means of the connecting brace 40 having the angular extensions 41 and 42 for engaging the rack bar and rod respectively. A frame 43 has its lower ends 15 secured to the sides of the cylinder 10 and extends above the top thereof and is provided with vertically disposed plates 44 and a removable top 45 forming a bearing in which the rod 26 reciprocates. A shaft 46 20 is mounted between the plates 44 and is provided thereon with the large and small gears 47 and 48, the former engaging another small gear 49 while the latter engages the teeth of the rack bar 39. The gear 49 is 25 supported upon a shaft 50 mounted between the plates 44 and having secured to one end thereof the operating handle 21 adapted to be rotated in both directions to reciprocate the valve 30.
- 30 It is further proposed, in connection with the present invention, to register the total number of gallons of liquid dispensed by the pump and also register the number of gallons dispensed at one time and, for this 35 purpose, there are provided the registers 52 and 53 for indicating such registrations, respectively, said registers being of any well known type and are therefore only shown conventionally in the accompanying draw-

ings. The register 52 is operated through 40 the medium of a gear 54 mounted upon the shaft 46 and engaging a movable portion of said register, as clearly shown in Fig. 4, it being understood that said register is only designed to record when the valve 30 is 45 moved upwardly to discharge liquid from the cylinder. The register 53 includes an arm 55 arranged in the path of movement of a projection or pin 56 carried upon the lower end of the rack bar 39 so that each 50 time said rack bar is raised the arm 55 will be oscillated to register the contents of the cylinder 10.

What is claimed is:—

A pump for attachment to a barrel comprising a cylinder, a frame sustained from the cylinder, a piston in the cylinder having a rod extending exteriorly thereof, a rack bar connected at its upper end with the rod and disposed with its lower end portion in 55 direct slideable contact with the exterior of the cylinder, a pinion supported in the frame, operatively engaged with the rack bar and having a manually operable means for reversely rotating it, a suction tube depending from the cylinder and means carried by the suction tube at the base of the cylinder for engagement with the upper edge of the barrel.

In testimony whereof, we affix our signatures in the presence of two witnesses.

STANLEY R. HUGHES,
HARRY D. HUGHES.
